EINAR A. JOHNSEN, OF MOUNTAIN LAKES, NEW JERSEY.

CONDENSER.

Application filed January 11, 1924. Serial No. 685,527.

To all whom it may concern:

Be it known that I, EINAR A. JOHNSEN, a citizen of the United States, residing at Mountain Lakes, Morris County, and State of New Jersey, have invented an Improvement in Condensers, of which the following is a specification.

This invention relates to an improvement in surface condensers and more particularly to the manner in which the condenser tubes are employed and spaced. The general practice in surface condensers at the present time is to use a uniform size of tube in each given unit so that all the tubes carry the same quantity of circulating water. The heat transfer per unit of tube surface in a surface condenser is always greatest at the steam inlet which is generally placed at the top of the condenser and the heat transfer diminishes gradually toward the outlet for the condensate and non-condensable vapors which is usually placed at the bottom of the condenser. This is largely because of the higher initial velocity of the steam as it enters the condenser and because the surface of the condenser tubes adjacent the steam inlet is comparatively free from condensate and non-condensable vapors, whereas the inner and lower tubes are covered with a film of condensate to a greater or lesser extent which tends to heat insulate the tubes in the lower section of the condenser. It will be readily understood, therefore, that employing tubes of uniform size in a given condenser apparatus is a relatively inefficient practice.

I have found that by varying the size of the condenser tubes in a surface condenser and suitably spacing the same these difficulties may be overcome, and in carrying out the invention the condenser tubes are arranged in sections decreasing in size from the steam inlet to the condensate outlet. The smaller tubes obviously carry less circulating water than the larger tubes, assuming the head in the distributing water box is constant and the tubes are so spaced as to evenly apportion or distribute the work of the condenser as performed in the various tube sections. The advantages obtained in varying the sizes of the condenser tubes are, therefore, obvious and the more

important of these are to obtain a uniform distribution of the steam around all the tubes to obtain a greater efficiency and permit the use of a smaller unit and to obtain a substantially uniform temperature of the circulating water as the same leaves all the tubes and a resultant hotter condensate as the same is withdrawn from the condenser, as will be hereinafter more particularly described.

In the drawing:

Fig. 1 is a side elevation of a surface condenser, and

Fig. 2 is an end view on an enlarged scale showing a tube plate and the manner in which the tubes may be distributed in the condenser.

Referring to the drawing, the condenser shell is indicated at 10. This is provided with an exhaust steam inlet 11 preferably at the top thereof and condensed steam outlets 12, 13 and 14 at the bottom thereof, it being understood, however, that this illustration is merely diagrammatic as one or more outlets for the condensate and the non-condensable vapors may be employed. The usual tube plates are indicated at 15 and 16. The tube plate 15 is connected to the flange 17 of the condenser shell and between the same and the flange 18 of the water box 19 by suitable bolts in the usual manner or otherwise. The outer flange 20 of the water box is similarly connected to the flange 21 of the water box bonnet 22 in which there may be provided suitable hand holes normally closed by suitable hand hole covers 23. This water box 19 is also provided with the usual circulating water inlet nozzle 24.

In the same manner at the other end of the condenser the tube plate 16 is connected to the flange 25 at the end of the condenser and to the flange 26 of the water box 27 by suitable bolts or otherwise. The water box 27 has an outer flange 28 which is connected to a flange 29 of the water box bonnet 30 in which there may be a number of hand holes normally closed by hand hole covers 31. The water box 27 furthermore is provided with a circulating water outlet nozzle 32. Also as indicated in Fig. 1 of the drawing the outlets 12, 13 and 14 for the condensate and non-condensable vapors may be pro-

vided with valves indicated at 33 and connected to a common discharge pipe 34 communicating with a pipe 35 leading to the condensate pump and also a pipe 36 leading 5 to a suitable vapor cooler. None of these particular features, however, have any material bearing on the present invention and are merely described as illustrating a structure in which the invention may be 10 employed, this condenser being a one-pass apparatus, but obviously the invention is not limited to this type as it may be employed in a double, triple, or condensers in which the circulating water is caused to 15 pass and re-pass in opposite directions any desired or required number of times.

As illustrated in Fig. 2 the interior of the condenser shell may be divided into a plurality of sections or compartments by 20 suitable walls 37, 38, 39 and 40 or otherwise, this illustration being also merely diagrammatic. As illustrated, however, the partition walls as aforesaid divide the interior of the condenser into sections or compartments indicated at *a*, *b* and *c*. In each of these compartments the condenser tubes are also arranged in sections, each section having a plurality of different sized condenser tubes therein, the diameters of the 25 condenser tubes preferably varying from the upper portion of the shell or the exhaust steam inlet portion thereof toward the bottom of the shell or the condensed steam outlet portion thereof. As shown, the tubes 30 in each section are of three different sizes, that is three different diameters. For example, in the compartment *a* the inner tubes indicated at 41 are of relatively small diameter, the intermediate section or group 35 of tubes 42 are of a larger diameter, and the outer section or group of tubes 43 are of a still greater diameter. In a like manner, the tubes in compartment *b* are arranged in three sections of different diameters, the tubes in section 44 being of relatively small diameter, the intermediate section of tubes 45 being of a larger diameter, while the outer section of tubes 46 in this compartment are of a still greater diameter. 40 45 50 55

The same condition maintains in compartment *c*, in which the inner section of tubes 47 are of relatively small diameter, the intermediate section of tubes 48 are of larger diameter, and the outer section of tubes 49 are of still greater diameter.

As illustrating the advantage in employing condenser tubes of different diameters and grouping the same so that the tubes of larger diameter are adjacent the exhaust 60 steam inlet of the condenser and the tubes of the smaller diameter are adjacent the condensate outlet portion of the condenser, it will be seen, for example, that three one inch tubes spaced three inches between their 65 centers have a surface area per unit of length

substantially the same as four, three-quarter inch tubes spaced two inches between their centers. In spacing the tubes, as hereinbefore described, therefore there is a larger channel for the incoming exhaust steam as 70 the same enters the condenser which obviously permits of a more even distribution of the steam in the sections having the tubes of larger diameter. It will also be apparent that with a given constant head of circulating 75 water in the water box a tube one inch in diameter will carry nearly twice the quantity of water per unit of time as is possible for a three-quarter inch to carry. As the steam is condensed the volume and velocity 80 of the same decreases and consequently less space between the condenser tubes is required for an even distribution of the remaining uncondensed steam which is provided for by the increasingly diminishing 85 diameters of the condenser tubes from the steam inlet to the condensed steam outlet. Furthermore the tubes of smallest diameter being placed at the bottom of the condenser permits a closer spacing of these tubes which 90 is desirable for condensing the relatively small amount of steam remaining when the same reaches the sections of the condenser in which these tubes are placed. Also as these smaller tubes have a lesser core of 95 water the heat penetrates the same more readily and they are consequently more efficient than the larger tubes.

I claim as my invention:

1. In a single pass surface condenser, a 100 shell having an exhaust steam inlet and a condensate outlet, a plurality of tubes arranged in rows converging from the exhaust steam inlet to the condensate outlet, and also decreasing in diameter from the 105 exhaust steam inlet to the condensate outlet, thereby providing a substantially uninterrupted lane for the passage of the exhaust steam between each two rows of tubes.

2. In a single pass surface condenser, a 110 shell having an exhaust steam inlet adjacent the top thereof and a condensate outlet adjacent the bottom thereof, and a plurality of tubes arranged in sections, each section of the said tubes having a plurality 115 of groups of tubes of different diameters, the said tubes of different diameters in the several sections being arranged in rows converging from the exhaust steam inlet to the condensate outlet, thereby providing substantially uninterrupted lanes between each two rows of tubes for the passage of the exhaust steam.

3. In a single pass surface condenser, a 125 shell having an exhaust steam inlet adjacent the top thereof and a condensate outlet adjacent the bottom thereof, and a plurality of tubes arranged in sections, each section of the said tubes having a plurality of groups 130 of tubes of different diameters, the said tubes

of different diameters in the several sections being arranged in rows converging from the exhaust steam inlet to the condensate outlet, thereby providing substantially uninterrupted lanes between each two rows of tubes for the passage of the exhaust steam, there also being a substantially uninterrupted ex-

haust steam lane between each two of the said sections of tubes, which steam lanes are of greater area than the areas of the steam lanes between adjacent rows of tubes.

Signed by me this 28 day of December, 1923.

EINAR A. JOHNSEN.
